UNITED STATES PATENT OFFICE.

JACOB G. CROOKSTON, OF PITTSBURGH, PENNSYLVANIA.

SHAVING-KIT CONTAINER.

Application filed March 16, 1926. Serial No. 95,112.

My invention relates to a shaving kit container, more especially to a container for a safety razor and the usual shaving accessories.

5 It is among the objects of my invention to provide a shaving kit container of small, compact construction which shall be suitable for packing a razor, shaving brush and soap container in a convenient and accessible 10 manner.

It is another object of my invention to provide a shaving kit container which shall embody a mounting member for a safety razor to which the several parts of the razor 15 may be securely fitted and which shall be adapted to be moved out of place to provide access to the shaving brush underneath.

Various kinds of shaving kit containers have been heretofore proposed which generally 20 consisted of a casing provided with suitable partitions corresponding in shape to the form of the implements that were packed therein, and on account of their structure they were ordinarily of a bulky 25 nature if provision were made to contain all of the shaving implements such as razor, brush and soap container, while those of the less bulky type were usually provided with means for packing the razor and its accessories such as the blades separately, with no 30 provision being made for brush and soap container.

In accordance with my present invention I provide a shaving kit container which is 35 adapted for packing all of the shaving implements within a very small space, there being but a single partition in the casing member which is preferably hinged thereto to permit moving it out of place, and this 40 partition member is so designed that all of the razor elements may be firmly secured to it on its upper side leaving sufficient space for a shaving brush to be disposed underneath.

45 In the accompanying drawing constituting a part hereof and in which like reference characters designate like parts, Fig. 1 is a view in perspective of a shaving kit container embodying the principles of my 50 invention and having a razor and brush arranged in it; Fig. 2 is a perspective view of a soap container adapted to fit into the container casing; and Fig. 3 is a view in perspective illustrating the shaving kit container with all of the shaving implements removed.

Referring to Fig. 3 of the drawing the container comprises a casing 1 which may be of general rectangular form having a cover 2 hinged to one of its sides, and having a partition member 3 secured at one of its ends as by a hinged joint 4. The partition 3 includes an offset end 5 having a portion 6 which is shaped complementary to a guard A and clamp B (Fig. 1) of a safety 60 65 razor, which razor parts are adapted to seat on the partition. The portion 6 is further provided with perforations or openings 7 adapted to receive the depending lugs and stem portions of the razor clamp member which project through the blades and the guard. A spring clip 8 is secured at its lower portion 9 to the partition 3 in any suitable manner as by riveting, soldering or welding, and functions to receive the razor 70 75 handle C and to hold it with sufficient firmness to cause the end of the handle to retain guard A and clamp B in position.

As shown in Fig. 1, a shaving brush E may be disposed underneath the partition 80 member 3 with its head portion fitted into the enlarged space underneath the spring clip and with the bristle end of the brush disposed underneath the offset portion 6 of the partition, it being understood that the bristle 85 end of the brush yields and offers slight resistance to the closing of the partition member to the position shown. The soap container, Fig. 2, is placed in the casing 1 in front of the brush and partition member 3 90 and does not interfere therewith.

The several elements are assembled in the container as follows: The brush E is placed in its position as shown in Fig. 1, the razor is assembled on the partition 3 in the 95 manner previously explained, and as illustrated, and the partition member is moved from its vertical position as shown in dotted lines to its horizontal position parallel with the bottom of the casing. The soap 100 container F may then be inserted and the casing cover 2 closed, thus rendering the shaving kit container a compact and solidly filled package.

105 It is evident from the foregoing description of my invention that a safety kit container made in accordance therewith provides an inexpensive, durable, compact container for shaving implements which is relatively inexpensive to manufacture and convenient and accessible for use, especially 110 for traveling.

Although I have described a specific embodiment of my invention, it will be obvious to those skilled in the art that modifications may be made in the details of construction and in the arrangement of the several cooperating parts without departing from the principles herein set forth.

I claim:

1. A shaving kit container comprising a casing having a cover, and a partition supported at the upper edge of one side of the casing, said partition having a downwardly offset portion affording a support for the guard and clamp of a safety razor, and the elevated portion of the partition being provided with means for receiving and detachably engaging a handle of a razor and for holding the handle firmly above said razor parts resting on the downwardly offset portion of the partition to retain them in position.
2. A shaving kit container comprising a casing having a cover, and a partition supported at the upper edge of one side of the

casing, said partition having a downwardly offset portion affording a support for the guard and clamp of a safety razor, and the elevated portion of the partition being provided with a spring clip for receiving the handle of a razor and for holding the handle firmly above said razor parts resting on the downwardly offset portion of the partition to retain them in position.

3. A shaving kit container comprising a casing having a cover, and a partition hinged at one end of the rear portion of an end of the casing, the outer end of said partition being downwardly offset to afford a support for a guard and clamp of a safety razor, and the inner elevated end of said partition being provided on its top with a spring clip to receive an end of the handle of a safety razor the other end of which handle projects over said downwardly offset portion of the partition to hold the clamp and guard in place.

In testimony whereof, I sign my name.
JACOB G. CROOKSTON.
